PIANO SHUTTER

Original Filed Dec. 3, 1924 2 Sheets-Sheet 2

FIG. 3

UNITED STATES PATENT OFFICE.

JOHN HAYS HAMMOND, JR., OF GLOUCESTER, MASSACHUSETTS.

PIANO SHUTTER.

Application filed December 3, 1924, Serial No. 753,558. Renewed November 30, 1928.

This invention relates to improvements in stringed musical instruments and more particularly to a piano having a shutter control for varying the intensity of sound.

5 It is the object of the present invention to provide an improved stringed musical instrument such for example as a piano having substantially sound proof casing with means provided on the casing for variably 10 controlling the intensity of sound emitted therefrom.

Another object of the invention is to provide an improved pedal control for use with a piano whereby the shutter mechanism may 15 be operated.

In ultra modern music the piano is being utilized as one of the instruments of a symphony orchestra. An example of a composition in which this is the case is Stravinsky's "Noches".

Broadly stated it is the object of the present invention to provide an improved control means for a piano, so that the volume of sound emitted therefrom may be very carefully 25 regulated and thus the instrument may be utilized for such purposes as one of the parts of a symphonic orchestra.

Other objects will appear from the following description taken in connection with 30 the accompanying drawing in which

Figure 1 shows diagrammatically one embodiment of the invention applied to a grand piano having a portion of the casing broken away;

35 Figure 2 is a section taken on the line 2-2 of Figure 1.

Figure 3 is a diagrammatic sectional rear elevation of a modified form of the invention, and

40 Figure 4 is a detail view of the strings.

In the following description and claims parts will be identified by specific names for convenience of expression but they are intended to be as generic in their application 45 to similar parts or equivalent construction as the art will permit.

50 Referring to the drawings in Figure 1 there is shown so much of a stringed musical instrument of the type commonly designated as a grand piano as is necessary to an understanding of the invention, having a casing 10 supported on suitable feet such

as 11, 12, 13, and having a manual 14 including keys for operating the playing mechanism.

55 The casing 10 is provided with a hinged cover 15 including a leaf 16 hinged thereto whereby the piano may be closed when desired, it being understood that when in a closed position the hinged cover 15 and leaf 16 are co-extensive with the opening in the top of the casing 10. A rod 17 is hinged to the side wall of the casing 10 for supporting the cover 15 in open position, the arrangement being such that the support 17 rests 60 within the casing when the cover is closed.

65 The side walls of the casing 10 are preferably constructed as shown in Figure 2 and are formed with a main wall portion 20 having a suitable veneer 21 on the outer 70 surface thereof and having an inner layer 22 formed of a material which is an absorbent of sound, such as felt or the like.

75 For producing sound within the casing 10 there is provided a plurality of differently tuned strings, such as 30 stretched over a usual metal framework. In proximity to the strings there is provided a sounding board 31, the construction and arrangement of the strings 30 of the sounding board 31, 80 being well known in the art and requiring no further detailed description. It is understood that the keys of the manual 14 are operatively connected with operating devices, such as hammers to cause the strings 85 or a group of strings tuned to the respective note to sound.

80 The mechanism may also include a pianissimo pedal 40 and a locking pedal 41 for adjustably positioning the hammers in order to produce a subdued or piano effect, 90 as is well known in the art. A loud pedal 42 may be provided for controlling suitable muffling means as is well known in the art.

95 For variably controlling the intensity of sound emitted from the instrument without requiring actuation of the muffling attachment or varying the position of the hammers, there is provided a plurality of series of shutters. I have shown one series of 100 shutters positioned over the strings 30 within the outline of the casing 10 and another series of shutters below the sounding board 31 and within the outline of the casing 10,

but it is understood that any other arrangement of groups of shutters may be employed if desired without departing from the spirit of the invention. Each series includes a plurality of shutters such as 43, 44, in the upper group of shutters and 45, 46 in the lower group of shutters which are pivotally mounted in bearings in the wall of the casing 10 so that they may be rotated about 10 their longitudinal axes. The upper group of shutters is provided with a connecting rod 47 extending transversely of said shutters and each is individually linked to each of the shutters of the respective group so that 15 transverse movement of the connecting rod 47 causes rotation of the shutters and thus opens or closes the passage therethrough for sound. The lower series of shutters is similarly provided with a connecting rod 48 20 similarly linked to respective shutters and operating in like manner.

For operating the groups of shutters there is provided a pedal 50 conveniently positioned with respect to the performer which 25 may be supported upon and keyed to a shaft 51 journalled in bearings of the brackets 52, 53 and having a bearing in the foot 12. The arm 54 is pinned to the rod 51 intermediate the length thereof and is operatively connected 30 through a broken link connection comprising an element 55 and an element 56 to a bell-crank lever 57 associated with the connecting rod 47 and a bell-crank lever 58 associated with the connecting rod 48. The bell-crank lever 57 thus operatively interconnects the element 56 and the connecting rod 47 being journalled in a bracket 59 secured to the wall of the casing 10. The bell-crank lever 58 forms an operative connection 40 between the element 56 and the lower connecting rod 48 and is journalled in a bracket 60 conveniently mounted on the frame of the instrument. The elements 55 and 56 are pivotally connected at 61.

In operation the performer uses the manual 14 in the customary manner to play the instrument. When it is desired to vary the intensity of sound produced in a more agreeable manner than is possible with the pedals 40, 41, 42 he operates the pedal 50. Rotation of this pedal in a clockwise direction with respect to Figure 1 causes movement of the arm 54 in a clockwise direction and downward movement of the element 56. By means of the bell-crank lever 57 downward movement of the element 56 is converted into movement with the connecting rod 47 towards the left of Figure 1 and the corresponding movement of the lower connecting rod 48 towards the left of Figure 2, thus increasing the openings between the shutters and increasing the intensity of sound. Rotation of the pedal 50 in a counter-clockwise direction reverses this movement and closes

the passages thus reducing the intensity of sound. The sound may thus be varied as may be desired, in accordance with the requirements of the music or the mood of the performer, and greatly improved control of 70 the intensity of sound may readily be obtained.

The performer is enabled to adjust the opening of the shutter passages with very great accuracy and without causing changes 75 from the music as written, such as sustained notes, as has been heretofore experienced with the so-called loud pedal of instruments of the prior art.

The performer can also easily reduce the 80 volume of sound and control the reduction with accuracy very much greater than is possible with the pianissimo pedal heretofore employed and thus the music may be rendered with wider variations of expression 85 than has heretofore been possible and made more agreeable to the ear.

In the modified embodiment shown in Figure 3, there is shown a stringed musical instrument of the same general type as in 90 Figure 1. The instrument comprises a casing 10 supported on suitable feet such as 12, 13 as has been described in connection with Figure 1.

For producing sound within the casing 10 there is provided a piano-forte action shown 95 diagrammatically as at 70 which may include strings and sounding board means as in the embodiment of Figure 1.

The mechanism may also include a loud 100 pedal 40 and a locking pedal 41 of conventional construction. The mechanism may also include a conventional hammer control attachment, schematically indicated at 71, which may be operated in a well known manner, by means of a pedal 72. The pedal 72 is linked to the hammer control mechanism 71 by means of a bell crank lever 73 and links 74, 75. It is understood that when the 105 pedal 72 is depressed, the link 75, bell-crank lever 73 and link 74 are moved, and the mechanism 71 is actuated in order to cause the hammer mechanism to shift with respect to the strings. In a grand piano this is 110 effected by shifting the hammers to strike a reduced number of strings, and in an upright piano it is effected by shifting the hammers into closer relation with the strings. Thus a reduced volume of sound is produced by 115 the strings. Upon release of the pedal, the hammer control mechanism is restored to 120 normal in the usual manner.

For simultaneously controlling the emission 125 of sound from the instrument so as to increase the effects of the regulation of sound, there is provided a plurality of series of shutters. One series of shutters, such as 130 the shutters 80 is positioned over the piano-forte action 70 and another series, such as

the series 81, 81 is positioned below the action, and within the outline of the casing 10. Each of said shutters is rotatably mounted to rotate about its longitudinal axis. The 5 shutters of each series are so spaced as to close the sound passage effectively when the respective shutters of the series are substantially in alignment. Each shutter is provided with an outwardly extending arm such 10 as 82. The upper group of shutters is provided with a connecting link 83 interconnecting all of the arms 82 of the upper series of shutters. The lower group of shutters is provided with a connecting link 84, inter- 15 connecting all of the arms 82 of the lower series of shutters. The upper connecting link 83 and the lower connecting link 84 are operatively interconnected by a pair of bell-crank levers such as 85—85, each pivotally 20 mounted on the casing 10, and a rod 86 interconnecting said bell-crank levers. The lower connecting link 84 engages a bell-crank lever 87, by means of a pin and slot connection, the bell-crank lever 87 being pivotally 25 mounted on a depending fixed bracket 88. The other end of the bell-crank lever 87 is pivotally connected with a rod 89, the other end of which is pivotally connected with a pedal 72. 30 For returning the shutter mechanism to normal after having been actuated, there is provided a retractile spring 90, secured at one end to an ear 91 from a part of the fixed casing 10, and the other end being secured to 35 an ear 92 from a part of the connecting link 84. In the operation of the form of the invention shown in Figure 3, the performer causes sound to be produced within the casing 10 in the usual manner. When it is desired to vary the intensity of sound emitted, particularly to increase the volume of sound, the pedal 72, is depressed by the foot of the performer into the position shown in Figure 3. The hammer control mechanism 72 is 40 thus actuated and causes the sound to be reduced in volume, at the same time the shutter mechanism comprising the links 83, 84, 85, 86, 87 and 89 to be operated, and thus the shutters 81 are adjusted into the open position as shown in the drawing. Upon releasing the pedal 72, the hammer control mechanism 71 is restored to normal in the usual manner, and the shutters 81 are again closed by virtue of the action of the retractile 45 spring 90.

The invention upon which the application is based is broader than the specific embodiments shown and described, for example, the structure selected for purposes of illustration is that of a piano but it is understood that the invention may be readily applied to any other form of musical instrument as may be desired.

What I claim is:—

65 1. In a musical stringed instrument, the

combination with a piano, of means for suppressing the sound produced thereby including a casing having a layer of sound insulating material, and having openings for the emission of sound, a plurality of 70 normally open centrally pivoted closures controlled entirely at the will of an operator, a single pedal for variably closing said closures for controlling the intensity of sustained notes, and means operatively in- 75 terconnecting said pedal and said closures.

2. In a musical stringed instrument, a plurality of strings, a sounding board adjacent said strings, a casing having sound openings and including a substantially 80 sound proof layer for effectively suppressing sound, a pair of groups of normally open centrally pivoted closures for said openings, each group of closures being parallel with and spaced from the sounding 85 board and forming when closed in combination with the casing a pair of resonant chambers, a single pedal for actuating said closures for variably controlling the intensity of musical sound emitted from the 90 instrument.

3. In a musical stringed instrument, a plurality of tuned strings, a sounding board adjacent said strings, means for variably suppressing sound produced by said strings 95 including a casing having sound openings and including a layer of substantially sound proof material and a plurality of normally open centrally pivoted closures for said openings positioned adjacent said strings 100 and parallel therewith for variably suppressing sound directly emitted therefrom, a second series of normally open and centrally pivoted closures positioned adjacent said sounding board and parallel therewith 105 for suppressing sound transmitted through said sounding board, and a single pedal for actuating all of said closures.

4. In a musical instrument of the percussive type, the combination with tuned 110 strings, of a casing having oppositely disposed apertures, controllable closures for said apertures and having boundary walls intermediate said apertures each provided with a layer of substantially sound proof 115 material.

5. In a piano, a casing, a piano movement in said casing including hammers and strings, said casing having an opening, a closure device for said opening, means for shifting said hammers and strings relatively to reduce the sound generated, and a single means controllable by the will of the operator for simultaneously operating said shifting means and moving said closure device 125 to closed position.

6. In a piano, a casing having sound insulating walls, a piano movement in said casing including hammers and strings, said casing having an opening, a closure device 130

for said opening, means for shifting said hammers and strings relatively to reduce the sound generated, and a single means controllable by the will of the operator for simultaneously operating said shifting means and moving said closure device to closed position.

7. In a piano, a casing, a piano movement in said casing including hammers and strings, said casing having an opening, a closure device for said opening, means for shifting said hammers and strings relatively, and a single means controllable by the will of the operator for simultaneously controlling said shifting means and closure device.

8. In a musical instrument, a casing, a source of sound within said casing, devices for controlling the amount of sound generated by said source, devices for controlling the amount of sound emitted from said casing, and a single means controllable by the will of the operator for simultaneously operating said devices.

25 9. In a piano, a casing, a piano movement

in said casing including hammers and strings, said casing having an opening, a closure device for said opening, a hammer shifting pedal, apparatus connecting said pedal and said hammers, and apparatus connecting said pedal and device, whereby said hammers are shifted to soften the sound and said device is moved toward closed position simultaneously by movement of said pedal.

10. In a grand piano, a casing, a piano movement in said casing including hammers and strings, said casing having oppositely disposed openings above and below said movement, a closure device for each of said openings, a hammer-shifting pedal, apparatus connecting said pedal and said hammers, apparatus connecting said pedal and devices, whereby said hammers are shifted to soften the sound and said devices are moved toward closed position simultaneously by movement of said pedal.

Signed at New York, in the county of New York and State of New York, this 28th day of November, A. D. 1924.

JOHN HAYS HAMMOND, JR.
